UNITED STATES PATENT OFFICE.

CHARLES BRITTIAN DRAKE, OF NORFOLK, VIRGINIA.

VULCANIZER.

1,255,588.

Specification of Letters Patent.

Patented Feb. 5, 1918.

Application filed July 2, 1917. Serial No. 178,203.

To all whom it may concern:

Be it known that I, CHARLES B. DRAKE, citizen of the United States, residing at Norfolk, in the county of Norfolk and State 5 of Virginia, have invented certain new and useful Improvements in Vulcanizers, of which the following is a specification, reference being had therein to the accompanying drawing.

10 This invention relates to portable vulcanizers adapted to be carried on the person or in the usual tool kit or box of motor vehicles, and to be used primarily in applying patches to inner tubes.

15 The invention has for its object the provision of a simple, inexpensive, and practical device of the character stated.

A convenient and the preferred embodiment of the invention comprises a vulcanizer implement, the component parts of which in one position constitute a clamping and heating means for the tube and applied patch, and in another position constitute a container for patches and the like; a part 20 of the clamping means being utilized to also serve as fastening means to secure the container in closed position; the clamping instrumentalities for the tube and patch being constructed to have a universal movement or play to the end that the clamping faces may assume parallelism while the rubber is being vulcanized; and one of the clamping faces being so associated with this carrying part of the container that it may 25 be offset into a projecting position from the adjacent surface of said part, when performing its clamping and vulcanizing function, and may be restored to a common plane, that is a plane coincident with the adjacent surfaces of the clamping member 30 and the part carrying the same to avoid the offsetting or projecting of the clamping part when the container is in closed condition.

40 All of the foregoing desirable characteristics of the particular embodiment of the invention to which I have alluded will be better understood, and the improved details in construction and arrangement of parts will also be made clear from the specific description hereinafter contained when read in connection with the accompanying drawings, wherein the said pre-

ferred embodiment of the invention is illustrated.

In the drawings:

Figure 1 is a perspective view of the device in its closed or container position;

Fig. 2 is a perspective view of the device in clamping or vulcanizing position;

Figs. 3 and 4 are longitudinal sectional 60 views of Figs. 1 and 2;

Figs. 5 and 6 are transverse sectional views of the same figures; and,

Fig. 7 is an end view of Fig. 1.

Referring more specifically to the drawings, wherein like reference letters designate corresponding parts of the several views, A represents the bottom member having a flange B extending around the sides and front end but open at the back as at D, and 70 C represents a top member having side flanges E and an open end F.

A hinged plate G is hinged along one edge as at H to the back edge of the bottom member A, and this hinged plate,—or 75 what may be termed the rear end closure,—is also indirectly hinged as at I to the top of the upper member C through the medium of a member J pivoted centrally as at K to the hinged plate to permit transverse rocking 80 movement of the member C on the hinged plate, when opened for a purpose as will later appear, the adjacent edges of the hinged plate being cut away or rounded as at L to permit this rocking movement. 85

The forward end of the member C is curved as at M to correspond with the curvature of the closed forward portion of the flange on the bottom member A and thereby, together, to form a circular opening N 90 in which a clamping and vulcanizing member O is centrally located and pivoted at opposite points by headed pins P to the arms Q of the member C bordering its cut-away or curved end. The clamping member O is in the nature of a cup capable of having its position reversed and the same is mounted for the pivotal movement on the pins referred to by means of ears R in which are oppositely disposed bayonet 100 shaped slots S receiving the shanks of said headed pins, the short ends of said slots projecting in the same direction circumferentially of the circular clamping member so

that by the rotary movement of the latter, the pins will be engaged with the horizontal shoulders to hold the clamping member in the projected position shown in Fig. 2, or 5 with the vertical portions of the slots to permit the clamping member to be forced inwardly to have its face in approximately the plane of the face of the upper member C when the device is not in use, it being 10 here understood that when the clamping member is in vulcanizing position it should be offset from or projected away from the face of the member C to coact properly with the opposing bottom (then the upper) 15 face of the lower member C, when the members A and C are reversed back to back as is of course readily understood from the drawings. The transverse rocking movement of the clamping member O on the pivot 20 pins enables the clamping face of said member to adjust itself notwithstanding the angularity of the members A and C when the device is opened with the members A and C reversed, as stated, and the pivot at the 25 back of the members C which carries the clamping member and permits said member C, and incidentally the clamping member O, to rock transversely, coöperates to give the clamping member O a universal play to all 30 extent that is necessary to bring the clamping faces into parallel relation.

Adapted to fit the interior of the cup-shaped clamping member is a heater T, itself in the nature of a flanged cup adapted to 35 fit the cup-like clamping member, and formed of metal with the integral spiral rib U coiled about the interior thereof, the purpose of this device being to contain the little liquid adapted to be burnt and to generate 40 adequate heat to be transmitted through the clamping member O to the rubber tube and patch inclosed between the clamping faces when the patch is to be vulcanized to the tube, which operation will be readily understood. 45

The upper member C is provided with a smooth apertured portion V, while the bottom member is provided with an approximately alined apertured portion W, said 50 apertured portion being adapted to receive a thumb screw X to clamp the container either in its closed condition as shown in Fig. 1, or in its clamping position with the container members reversed as shown in 55 Fig. 2.

The interior of the container is of a size to carry a number of patches, as represented at Y, or a number of combustible disks represented at Z and composed of any suitable 60 material, known in the art, for creating the necessary heat to insure vulcanization, the disks being adapted to be employed when the liquid burner previously alluded to is not to be used.

65 When the container is partially empty, so

that there is room therefor, the clamping part O may be swung around into a reversed position on its pivots so that the clamping face may be forced into the interior of the container and thereby preserve such face 70 against damage. This is indicated in full lines in Fig. 5, the other inclosing position of the clamping part O being shown in full lines in Fig. 1 when the container is initially filled with supplies. 75

It is believed unnecessary to further outline the operation of the device inasmuch as this will be clear from the foregoing description of the structure and purposes thereof. 80

While I have herein disclosed a special embodiment of the invention it will be understood by persons skilled in the art to which the invention relates that the same is capable of embodiment in still other forms 85 and devices without departing from the spirit of the invention.

Having thus described the invention, what I claim is:

1. A combined container and vulcanizing 90 device comprising oppositely disposed members connected to occupy a closed position or a reversed clamping position and a common means for securing the members in closed or clamping position. 95

2. A vulcanizing device comprising oppositely disposed combined container and clamping members hinged to occupy reversed positions, and clamping means for the device when in reversed positions. 100

3. A vulcanizing device comprising oppositely disposed combined container and clamping members hinged to occupy reversed positions, and clamping means for the device when in reversed positions, the means 105 connecting the opposite members together enabling swinging movements of one of the members both longitudinally and transversely.

4. A vulcanizing device comprising oppositely disposed combined container and clamping members hinged to occupy reversed positions, and clamping means for the device when in reversed positions, the means connecting the opposite members together enabling the swinging movements of one of the members both longitudinally and transversely, and said member carrying a movable clamping face mounted to swing in a direction transverse to the lateral movement of the member which carries the same. 110

5. A vulcanizing device comprising clamping members, one of said members including a supporting part mounted for transverse rocking movement and also a movable 115 clamping face mounted for movement at right angles to said transverse movement.

6. In a vulcanizing device inclosing combined container and clamping members open at the rear, a hinged plate secured to one 120

130

of the members to permit reversing of the members from confining to clamping position, and means pivoting the other member to said hinged plate to permit said member to swing in a lateral direction.

7. A vulcanizing device of the character described comprising opposing container and clamping members adapted to be reversed from the containing to the clamping position, one of said members carrying a pivoted packing face adapted to be projected beyond the adjacent plane of the member which carries the same when in clamping position.

8. A vulcanizing device of the character described comprising opposing container and clamping members adapted to be reversed from the containing to the clamping position, one of said members carrying a pivoted packing face adapted to be projected beyond the adjacent plane of the member which carries the same when in clamping position, and to be withdrawn into approximately the same plane when in closed position.

9. A vulcanizing device of the character described comprising opposing container and clamping members adapted to be reversed from the containing to the clamping position, one of said members carrying a pivoted packing face adapted to be projected beyond the adjacent plane of the member which carries the same when in clamping position, and to be withdrawn into approximately the same plane when in

closed position, said clamping face including a disk like part and pivot and bayonet slot connections between the same and opposite portions of the member carrying the same.

10. A vulcanizing device of the character described comprising combined container and clamping members adapted to have their positions reversed, one of said members carrying a movable clamping part, the latter being cup-shaped, and a liquid burner associated therewith.

11. A vulcanizing device of the character described comprising combined container and clamping members adapted to have their positions reversed, one of said members carrying a movable clamping part, the latter being cup-shaped, and a liquid burner associated therewith and removable therefrom.

12. A vulcanizing device of the character described comprising combined container and clamping members adapted to have their positions reversed, one of said members carrying a movable clamping part, the latter being cup-shaped, and a liquid burner associated therewith, the said burner being also cup-shaped and having heat radiating projections disposed on the interior thereof.

In testimony whereof I hereunto affix my signature in the presence of two witnesses.

CHARLES BRITTIAN DRAKE.
